UNITED STATES PATENT OFFICE

ALFRED J. MACY, OF EVANSTON, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT GAS BOMB

Application filed July 6, 1928, Serial No. 41,729. Renewed March 25, 1930.

This invention relates to mechanism for releasing a noxious gas into the interior of a vault when an attempt is made to gain forcible entry thereto.

It is an object of this invention to provide a gas bomb normally sealed, together with means for breaking said bomb and means for normally restraining said first-mentioned means, the latter means being distributed over the vulnerable portions of a vault or the vulnerable portions of a vault or closure in positions subjecting it to damage or severance upon cutting or burning a hole therethrough.

Heretofore, supplemental locking means have been provided adapted to be actuated by attempts at forcible entry, and gas bombs have been incorporated with such locks in such a way as to release a noxious vapor upon actuation of the supplemental lock. I have found that under ordinary circumstances a gas bomb alone serves as an effective protection for vaults, as the noise of discharge serves as an alarm and the gas-filled vault effectively precludes entry for a period long enough to force a burglar to abandon the attempt at entry. An advantage in the use of a gas bomb alone is in the elimination of the difficulty of unfastening the supplemental lock when once operated, as the lock is as effective in barring the rightful users of the vault as in preventing burglary thereof. It is therefore an object of this invention to provide a vault gas bomb and bursting mechanism therefor adapted to be normally restrained by a self-contained flexible mechanism which may be placed over the most vulnerable parts of a closure.

It is also an object of this invention to form a gas bomb as a continuation of a cartridge barrel whereby the burning gases which propel the cartridge bullet also serve to expel and vaporize a noxious gas-producing fluid.

Other and further important objects of this invention will be apparent from the disclosures in the specification and accompanying drawings.

The invention, in a preferred form, is illustrated on the drawings and hereinafter more fully described.

This invention may be placed on the walls, and other parts of a vault enclosure as well as partially built into the walls, and floor. For clearness of description the specific embodiment of this invention, chosen for illustration, has been shown as applied to the inner surface of a vault door.

On the drawings:

Figure 1 shows a rear elevational view of a vault door with the device of this invention installed thereon.

Figure 2 is an enlarged section of the gas bomb at the instant of release of the firing plunger.

Figure 3 is a fragmentary section of a portion of Figure 2 showing the normal locked position of the firing plunger.

Figure 4 is a section on the line IV—IV of Fig. 2.

Figure 5 is a section on the line V—V of Fig. 3.

As shown on the drawings:

A diagrammatic view of the back or inner surface of a vault door 10 is shown in Figure 1 together with the usual locking mechanism 11 therefor. Disposed over the surface of the door is a tube 12 formed of a coiled wire, without spacing between the coils, in order to resist compression, the tube containing a plain wire 13. The tube and wire therein are flexible and the wire is intended to be a free running fit in the tube even when the latter is bent to a small radius. The free end of the tube at 14 is soldered or otherwise secured to the wire 13 at this point and the other ends of both tubes and wire are fastened to members of the gas bomb shown in Figure 2.

This bomb comprises a sealed flask 15 of glass or the like containing a volatile liquid which when released forms a noxious gas such as the well-known "tear gas". This flask is protected from accidental injury by a casing 16 formed of a tube screwed into top and bottom caps 17 and 18, the top cap extending upwardly and being apertured for two or more cartridges 19. The cartridges shown are of the rim fire variety so that a circle of such cartridges can be fired by a single central firing pin 20. The cartridges are held down while discharging by the 190

washer 21 which is clamped in position by the tube 22 which serves as a guide for the firing plunger 23 carrying the pin 20 and which is downwardly impelled by the spring 24.

The trigger or releasing mechanism for the firing plunger is housed in the centrally apertured casing 25 screwed to the tube 22 and having an annular groove 26 in the wall 10 of the central aperture. This mechanism comprises an elongated cup-like member 27 slideable in the casing aperture and fitting over a head 28 of reduced diameter on the top of the firing plunger. This head has an 15 annular groove 29 similar in form to the groove 26 in the casing 25. The cup member 27 is diametrically apertured for a pair of balls 30 of a diameter exceeding the wall thickness of the cup member so that the balls 20 will project into either the groove 29 or 26 to respectively hold or release the firing plunger. Mounted above the casing 25 is a second tube 31 serving as a guide for the block 32 to which the end of the coiled tube 25 12 is secured. The wire 13 passes down through this block and is attached to the top of the cup member 27 at 33. A spring 34 is interposed between the block 32 and the casing 25 to place the wire 13 under tension and 30 the tube 12 under compression, and this spring also serves to permit differential movement of the tube and wire due to shifting the layout of the tube or from temperature changes without releasing the firing mechanism. 35

The operation

The disposition of the tube 12 containing the wire 13 over the surface to be protected primarily depends upon the relative vulnerability or likelihood of an attack being directed to particular parts thereof. In a door, for example, an attempt to gain entry by cutting or burning a hole therein might be directed towards the combination lock or towards one of the corners of the door, so that the tube is passed over such places. The tube may be held in place by a variety of ways as by tying to various parts of the structure or by means of common pipe staples, or it may be embedded in mortar or concrete where such material is used. The operation of burning or cutting a hole through the closure would necessarily result in melting the tube and wire or cutting the same as the tube and wire are preferably of a material of the same or lower fusing point as the closure. 55

Severing the tube and wire from any cause 60 releases the wire which is pulled through the tube by the spring 34. At the same time, the firing plunger spring acts to pull the top of the firing plunger down which carries the cup member 27 down therewith until the balls 30 65 can pop out into the groove 26 in the casing

25 whereupon the firing plunger is entirely freed from the wire 13 and descends to strike and discharge the cartridges. The bullet from the cartridges break the gas bomb and the gases generated by the burning powder serve as an efficient ejector for the content of the bomb through the aperture provided in the lower cap 18 of the casing, the bullet having effectively broken both the top and bottom of the gas flask. The high gas pressure generated by the powder has both an expelling and a vaporizing action on the fluid used in the gas bomb thus giving improved results because of forming the gas flask in closure as a part of the barrel formed by the cartridge mounting.

I am aware that numerous details of construction may be varied through a wide range without departing from the principles of this invention and I therefore do not purpose limiting the patent granted hereon, otherwise than necessitated by the prior art.

I claim as my invention:

1. The combination with a sealed flask containing a noxious vapor, of an apertured enclosure therefor, cartridges mounted to discharge through said flask, firing mechanism for said cartridges, comprising a firing plunger, restraining means therefor comprising a sleeve on the portion of the plunger carrying a plurality of balls in apertures in the wall thereof, said balls being adapted to normally project into a groove in said firing plunger to hold the same, a casing for said sleeve having an inner groove adapted to receive said balls upon a displacement of said sleeve to permit release of said firing plunger, and a flexible fracturable connection extending beyond said firing mechanism and normally holding said sleeve from movement in said casing.

2. In combination flexible enclosing means, flexible means movable therein and secured at one end to said enclosing means, a gas bomb, means for bursting said bomb, and connections between the bursting means and said enclosing means, said flexible means adapted to permit actuation of said bursting means upon relative movement between said enclosing means and said flexible means.

3. A device of the class described comprising a sealed flask, an enclosing casing therefor, a cartridge holder mounted in said casing with its discharge opening pointing towards said flask, a firing plunger, a trigger mechanism therefor, and means normally restraining said trigger mechanism and adapted to release said trigger mechanism upon severance of the restraining means.

4. A device of the class described including in combination a cartridge discharging mechanism having a barrel, a casing in line with the barrel, a sealed gas flask confined in said casing, and cartridge holding means in line with and between the barrel and casing, said cartridge holding means forming a de-

tachable connection between the barrel and casing sustaining the same in line with one another.

5. A device of the class described including in combination a cartridge holding and discharging mechanism, a casing connected in line with said mechanism, a sealed gas flask confined in said casing and adapted to be fractured by the discharge of a cartridge, and
10 means normally restraining operation of the cartridge discharging mechanism, comprising a flexible housing member extending beyond the holding and discharging mechanism, and a tension member in said housing
15 which upon severance releases the cartridge discharging mechanism for operation.

6. A device of the class described including in combination a cartridge holding and discharging mechanism, a casing secured in line therewith, a sealed gas flask confined in said
20 casing and adapted to be ruptured by the discharge of a cartridge, and means normally restraining the cartridge discharging mechanism comprising a flexible wire connected thereto and extending therebeyond, a housing member for the wire capable of flexure therewith and normally maintaining the wire under tension, the said flexible wire upon severance releasing the cartridge discharging mechanism for operation.

30 In testimony whereof I have hereunto subscribed my name.

ALFRED J. MACY.
